(57) **CLAIM**

The ornamental design of a luminous device for a vehicle, as shown and described.

DESCRIPTION

1. Luminous device for a vehicle

1.1 : Perspective

1.2 : Front

1.3 : Left

1.4 : Right

1.5 : Top

1.6 : Bottom

1.7 : Back

1.8 : Perspective

Lighting module for vehicles comprising a housing closed by means of a transparent glass through which one can see an optical lens in the middle encased in a mask; the central lens comprises an oblong central part and two lips situated above and below the central part.

The broken lines in the drawings illustrate portions of the luminous device for a vehicle that form no part of the claimed design.
